US00D918012S

(12) **United States Design Patent** (10) **Patent No.:** **US D918,012 S**
Wikstrom (45) **Date of Patent:** **** May 4, 2021**

(54) **TAMPER-EVIDENT BOX LOCK**

(71) Applicant: **Todd Wikstrom**, Las Vegas, NV (US)

(72) Inventor: **Todd Wikstrom**, Las Vegas, NV (US)

(**) Term: **15 Years**

(21) Appl. No.: **29/722,055**

(22) Filed: **Jan. 25, 2020**

Related U.S. Application Data

(63) Continuation-in-part of application No. 29/694,703, filed on Jun. 12, 2019.

(57) **CLAIM**

The ornamental design for a tamper-evident box lock, as shown and described.

DESCRIPTION

FIG. 1 is a perspective view of a tamper-evident box lock, showing my new design;

FIG. 2 is an enlarged perspective view thereof;

FIG. 3 is a top plan view thereof, the bottom plan view being a mirror image thereof;

FIG. 4 is a left-side elevational view thereof, the right-side elevational view being a mirror image thereof;

FIG. 5 is a front elevational view thereof; and,

FIG. 6 is a rear elevational view thereof.

The broken lines showing a pizza box in FIG. 1 depict environmental matter and form no part of the claimed design.

1 Claim, 3 Drawing Sheets
